UNITED STATES PATENT OFFICE.

GEORGE F. KELLER, OF LAVELLE, PENNSYLVANIA.

RAIL-JOINT.

1,173,979.

Specification of Letters Patent. Patented Feb. 29, 1916.

Application filed August 10, 1915. Serial No. 44,730.

To all whom it may concern:

Be it known that I, GEORGE F. KELLER, a citizen of the United States, residing at Lavelle, in the county of Schuylkill and State of Pennsylvania, have invented new and useful Improvements in Rail-Joints, of which the following is a specification.

The present invention relates to improvements in connecting the meeting ends of rail-
10 way rails, and an object of the invention is to provide a simple, effective and cheap de-
vice of this character whereby the wheels
of the rolling stock will be prevented from
leaving the rails when crossing the usual gap
15 between the rails, so that a substantially con-
tinuous rail is provided.

A further object of the invention is to so construct and connect the meeting ends of two railway rails that the same will be effec-
20 tively sustained against lateral movement and permitted only a limited longitudinal movement incident to the expansion and con-
traction of the rails.

With the above and other objects in view,
25 the improvement resides in the construction, combination and arrangement of parts set forth in the following specification and falling within the scope of the appended claim.

In the drawings: Figure 1 is a side elevation of two rails connected and constructed
30 in accordance with the present invention, Fig. 2 is a top plan view of the same, Fig. 3 is a bottom plan view of the same, Fig. 4 is a transverse sectional view taken approxi-
35 mately centrally through the joint, Fig. 5 is a perspective view of one of the rail ends, and Fig. 6 is a similar view of the chair.

Referring now to the drawings in detail, the numerals 1 designate two rails which
40 have their bodies of the ordinary construc-
tion, the said rails, however, adjacent their ends having their webs thickened so that the sides of the same are arranged flush with the sides of the heads. The rails, at the said
45 thickened portions are cut transversely and longitudinally to provide extensions 2, one of the faces of the said extension being flush with one of the sides of the rail, the opposite face being beveled from the end of the ex-
50 tension to the transverse cut which provides the shoulder which is designated by the numeral 3. The shoulder provided by the

said transverse cut at the base portion of the rail is indicated by the numeral 4. The inner inclined faces, indicated for distinction 55 by the numerals 5, of the extensions of the rails 1 are adapted to contact with the central vertically arranged rib 6 provided upon the central and channel portion 7 of a rail chair 8. The outer walls of the channel are 60 vertically straight and are indicated by the numerals 9 and the said walls 9 are adapted to contact with the outer straight walls or surfaces of the rail extensions 2. The thickness of the rib 6 is sufficient to provide for a 65 web engagement of the rail extensions between the same and the straight walls 9 and the said rib is also of sufficient length to permit of the ends of the rail extensions contacting with the shoulders 3 outwardly of 70 that contacted by the ends of the rib 6, while the shoulders 4 contact with the ends of the base portion of the chair.

The angularly disposed rib, as well as the rail extensions 2 are provided with suitable 75 alining bolt openings, through which pass the usual bolts which are provided with the ordinary securing nuts, and the outer longitudinal edges of the base of the chair may be inclined and notched, the said notches 80 providing pockets for the reception of securing spikes which enter the ties 10.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what 90 I claim is:

In a rail joint, two rails having their webs thickened at the ends thereof disposed flush with the sides of the head, the said ends being cut transversely, vertically and longitudinally to provide extensions, the outer faces of the extensions being flush with one of the faces of the head, the inner faces of the extensions being inclined from the ends thereof to the shoulder provided by the 95 transverse cut, and a chair including a channelled member having a centrally arranged angularly disposed rib projecting from the channel, said rail extensions adapted to be 100

received within the channel and to have their angular faces contacting with the opposite faces of the rib, and cut base portions engaging with the ends of said chair, trans-
5 verse means for securing the extensions to the rib, and means for securing the chair to the supporting ties.

In testimony whereof I affix my signature in presence of two witnesses.

GEORGE F. KELLER.
